UNITED STATES PATENT OFFICE.

SÉVERIN LAZARE DELEUIL, OF VINCENNES, FRANCE.

COLOR-PRINTING MACHINE.

SPECIFICATION forming part of Letters Patent No. 644,733, dated March 6, 1900.

Application filed September 22, 1898. Serial No. 691,599. (No model.)

To all whom it may concern:

Be it known that I, SÉVERIN LAZARE DELEUIL, constructor, a citizen of the Republic of France, residing at 124 Rue de France, Vincennes, France, have invented certain new and useful Improvements in Color-Printing Machines for printing in one or several colors on flat or relief surfaces, more especially on placards, boards, or the like, and particularly on enameled plates, of which the following is a specification.

This invention relates to a machine the object of which is to convey a color or an enamel of any desired tint by pressure into hollow plates, these hollows or recesses representing any characters, letters, figures, stereotypes, designs, or the like.

I have represented this apparatus in the accompanying drawings, in which—

20 Figure 1 shows in sectional elevation the upper part of the machine. Fig. 2 represents in side sectional elevation an upper part of the machine. Fig. 3 is a section on line X X of Fig. 1. Fig. 4 is an elevation of the mechanism for driving the piston. Fig. 5 shows the same parts in plan. Fig. 6 shows in plan a frame serving to receive the object to be printed upon, and Fig. 7 is a plan view of a stencil-plate.

30 As has been above stated, the object of this machine is to deposit upon placards, plates, and the like a layer of paint, enamel, or the like in a given form by means of pressure. For this purpose I have constructed my machine, by way of example, in the following manner:

In the upper part A' of a machine-frame A, supporting the whole mechanism, a plate B is provided, which is fitted with a piston B', 40 which latter receives a vertical alternating movement by the driving crank-shaft J and by a connecting-rod D with an ordinary bearing for the piston and an adjustable eccentric bearing C for the driving-shaft J. The 45 adjustment of the stroke of the plate B, by way of displacing the eccentric bearing, is obtained by means of a small external hand-wheel O, Fig. 2, the axis of which terminates in an endless screw O', adapted to gear with 50 a worm-wheel O'', formed on the bearing itself. The plate B is, moreover, guided laterally in guides A^X, provided in the frame A'.

Below the plate B the machine-frame is provided with a seat or bed a, upon which another frame is adapted to rest, which latter receives the plate or the like to be printed upon. In the center of this seat or bed an ejector E is arranged, which is connected to the piston of the cylinder I by means of a bellows E', provided for this purpose. 55

The piston I' of the cylinder I, which contains the viscid printing material, is rigidly connected with an endless screw X, receiving an ascending or descending movement by the rotation of a nut V, rigid with a worm-wheel 65 U. This screw X is normally guided by two sockets b, Fig. 1, and two guides c, fixed to the cylinder, and the cylinder, which is itself removable, is held in place by means of a hinged sleeve I². 70

The sleeve-sections are pivotally connected together by a vertical pin or pivot-bolt I³, and said sections when closed together engage under a flange f' on the cylinder to thereby hold the latter in place. The sleeve-sections have 75 ears f², which when the sections are closed together embrace a bolt I⁴ on the frame A, which may receive a thumb-nut to hold the sections firmly in place.

In order to permit of the frames and plates 80 or the like being handled, the upper part A' is made movable upon the machine-frame A. For this purpose the fixed part A of the machine-frame has a rack-bar H rigidly connected with it, which rack-bar is on its part 85 adapted to gear with a toothed pinion h, the axis of which, being supported in the movable upper part A' of the machine-frame, is provided upon its outside with an operating hand-wheel G, whereby the plate B can be 90 completely displaced.

The operation of the piston for pressing out the material located in the cylinder I is obtained by means of the driving-shaft J, which is provided at the side with a grooved cam P, 95 Figs. 1 and 4. This cam actuates an oscillating lever P', which transmits its movement to a similar lever Q by means of rods g, acting as connecting-rods.

Upon the free arm of the lever Q two pawls 100 R R' are pivotally connected, which are adapted to work on two ratchet-wheels S S'. One of these pawls and ratchet-wheels imparts to the piston, and consequently to the

printing material, the ascending movement by the intermediary of the shaft U' and gear-wheel U, while the other similar couple of working parts communicates to the piston 5 and to the material the opposite or descending movement.

The stroke of the pawls R R' is limited by the two levers v v', held in position at the desired distance by the rack-bars x x'.

- 10 The two movements of the piston are adjusted in their extent as required in order to permit of the changing of the plates, placards, or the like to be printed upon. For this purpose the band-wheel or pulley T is mounted 15 loosely upon the driving-shaft J, these two parts being rigidly connected by a bolt or pin K, actuated by a leaf or spiral spring i, the effect being to engage the bolt with the hub of the fly-wheel.
- 20 The stopping of the plate at the upper end of its stroke is effected by disengaging the bolt K from the hub, this disengagement being effected automatically by the action of a spring n and of bevel-edged oscillating levers L.
- 25 The actuation of the driving-shaft J by the band-wheel T is effected by operating a pedal N, connected to the lever L by a rod or connecting-rod m, which as it descends compresses the spring n, causes the lever L to oscillate, which in moving away from the bolt leaves the latter to the action of the spring i, which drives the same and engages it with the hub of the wheel or pulley, Figs. 1 and 3.
- 30 Fig. 6 represents a frame g, serving to receive the object to be printed upon. The same is fixed in the center part of the fixed machine-frame A. The distributing-plate e, with the substance to make the impression, 35 and also the frame g, (supporting the plate g² to be printed upon,) are seated upon springs g', which latter seat directly on seat a. The cut stencil-plate e² is fitted into grooves e' of plate e, from which the printing substance 40 issues through the holes representing letters, numbers, and other characters or designs just far enough to be even with the outer surface. The socket E of plate e has a flange E', to which is secured by screws v a flange E'', secured to the bellows. The bellows F when 45 the printing substance used is viscous or of rather great consistency becomes slightly dilated by taking in some of the substance forced back through the pressure exerted by the platen B, thus obviating the danger of spreading the substance over the stencil-plate e² and of producing blurred outlines on the printed material. The lower end of the bellows F is secured between a flange F' and the 50 flange of cylinder I, the flanges being connected together by screws v'. The bolt K, which can slide in a ring k' fast on shaft J, is adapted to enter the recess k in the hub of pulley T, said bolt being constantly impelled 55 toward and into the hub of the pulley by spring i. The disengagement between shaft J and pulley T is effected by releasing the foot-lever

N, by which then the rod m under the tension of the springs n operates the lever L and causes this latter to engage with its incline between the inclined head of the bolt K and the hub of the pulley, which then revolves free upon the shaft.

The operation of the apparatus is as follows: The pump barrel or cylinder I having 75 been charged with printing substance, the stencil-plate e² and the plate g² to be printed upon are arranged in their proper place. By now engaging together the shaft J and pulley T the printing substance is gradually but 80 very slowly forced to the level with the stencil-plate e², whereupon the platen B descends immediately and presses the plate g² for printing, together with its frame g, by compressing the springs g' thereof against the stencil-plate e² and so into contact with the printing substance level with the stencil-plate. At the moment when the plate is imprinted the shaft J and its connected parts, including the cam P, have only performed half a revolution, and during the next half-revolution the platen B is caused to ascend while the piston I' descends. If at the completion of the revolution the foot-lever is set free, the springs n' actuate the lever L to disengage the bolt 95 K from the pulley, thus stopping the mechanism and enabling the plate and, if desired, also the stencil-plate to be changed. To enable this to be effected by means of the hand-wheel G, pinion h, and rack H, (the pinion h being on shaft h⁵, which is mounted in bracket h⁶,) the portion A' of the frame is moved rearward, and after then having changed the plate as required the portion A' is replaced, and thereupon the foot-lever N is moved to 100 engage the pulley and the operation is repeated.

When it is desired to print simultaneously in two or more colors, I furnish my machine with the required number of additional cylinders similar to that shown in the drawings, each such cylinder containing a different color and leading by its upper end into one of the compartments formed in the distributing-plate e by means of vertical partitions 105 upon which is placed the stencil. These partitions may be fixed either to the plate e or to the stencil, as may be most convenient.

What I claim is—

1. In a color-printing machine, the combination with a frame, of a cylinder, a piston adapted to be reciprocated therein, a distributing-plate arranged above the cylinder and adapted to receive a stencil, a bellows arranged intermediate the distributing-plate 110 and the cylinder and a frame arranged above the distributing-plate and adapted to receive the sheets to be printed.

2. In a color-printing machine, the combination with a frame, of a cylinder, a piston adapted to be reciprocated therein, means for removably supporting the cylinder in position, a distributing-plate arranged above the cylinder and adapted to receive a stencil, a

bellows arranged intermediate the distributing-plate and the cylinder, and a frame arranged above the distributing-plate and adapted to receive the sheets to be printed.

- 5 3. In a color-printing machine, the combination with a frame, of a cylinder, a piston adapted to be reciprocated therein, a distributing-plate, a bellows, a frame to receive the sheets to be printed, all arranged as set forth, 10 a grooved cam P, a driving-shaft upon which said cam is mounted, a bell-crank lever, a second bell-crank lever, a rod connecting the said levers, ratchet-wheels S, S', pawls carried by the said second lever and engaging the 15 ratchet-wheels, a shaft carrying the ratchet-wheels, and having a worm portion, the worm-wheel U, nut V, and screw-rod X, all arranged as and for the purpose specified.

4. In a color-printing machine, the combi-

nation with a cylinder, and a piston adapted 20 to be reciprocated therein, of a platen adapted for reciprocation, a driving-shaft having a crank portion, a bearing-sleeve eccentrically mounted on the crank, a worm-wheel on the said sleeve, a shaft extending transversely 25 of the driving-shaft, a screw on the transverse shaft engaging the worm-wheel, and a connecting-rod having one end in connection with the platen and the opposite end mounted upon the bearing-sleeve.

In testimony that I claim the foregoing I have hereunto set my hand this 8th day of September, 1898.

SÉVERIN LAZARE DELEUIL.
